United States Patent Office

Des. 181,561
Patented Nov. 26, 1957

181,561

FLORAL DISPLAY HOLDER

Harold C. Voll, Toledo, Ohio

Application April 13, 1954, Serial No. 29,985

Term of patent 14 years

(Cl. D35—3)

FIG. 1

FIG. 2

FIG. 3

FIG. 4

Fig. 1 is a side elevational view of a floral display holder showing my new design;

Fig. 2 is a front elevational view thereof;

Fig. 3 is a rear elevational view of Fig. 1; and

Fig. 4 is a top plan view of Fig. 1.

The broken lines in Figs. 1, 3 and 4 are for illustrative purposes only.

I claim:

The ornamental design for a floral display holder, as shown and described.
